[57] CLAIM

The ornamental design of a sheep handler, substantially as shown and described.

DESCRIPTION

FIG. 1 is a perspective view taken from the top, front and left side of a sheep handler showing my new design; FIG. 2 is a perspective view taken from the top, rear and right side thereof;

FIG. 3 is a left side elevational view thereof, showing the handler in an open position, the right side being a mirror image of the left side shown; and

FIG. 4 is another left side elevational view thereof, showing the handler in a closed position.

Fig. 1.

Fig. 2.

Fig. 3.

Fig. 4.
